WELT SUPPORT FOR SOLE ATTACHING MACHINES

John B. Hadaway, Swampscott, Mass., assignor to United Shoe Machinery Corporation, Paterson, N. J., a corporation of New Jersey

Application November 19, 1934, Serial No. 753,571

15 Claims. (Cl. 12—33)

This invention relates to welt supports and is herein shown and described as embodied in a new and improved mechanism for supporting and pressing a welt or other marginally projecting portion of a shoe against the margin of the sole which extends beyond the last, in opposition to the pressure applied to the outer face of the sole in the sole attaching operation. It is to be understood, however, that the invention may be used in other machines where a similar structure or function is desired. In the present instance, the invention is shown as applied to a sole attaching machine in which a cemented sole is attached to a shoe by the application of pressure.

It is an object of the invention to provide an improved welt support which will be easily operable and adaptable to shoes of a wide range of sizes and shapes, and an important feature of the invention consists in the provision of a welt support which is vertically conformable in shape to the welt crease of a shoe, in combination with means for locking it rigidly in its conformed shape.

In a preferred form of the invention the welt support as a whole may comprise a series of separate feet, each attached to a yieldingly mounted leg, with means for simultaneously locking all of the legs against vertical yielding after the feet have been conformed to a welt crease, in order that the vertical contour of the welt shall be accurately preserved when pressure is applied to the sole, and the welt and the margin of the sole shall be pressed securely together.

Another feature of the invention which facilitates the operation of the machine upon a shoe resides in a sectional welt support provided with means, as a spring or springs, for conforming it to the welt crease of a shoe, and means for spreading apart the sections to permit the shoe to be readily inserted or removed.

Further features of the invention relate to improvements in details of the welt engaging feet and other parts of the mechanism, all contributing to ease and speed of operation and superior results.

A more complete understanding of the invention will be gained from reading the following detailed description of a preferred embodiment thereof in connection with the accompanying drawings, in which

Fig. 1 is a view in front elevation of a portion of a sole attaching machine equipped with a welt support embodying the invention;

Fig. 2 is a view on an enlarged scale with the

welt support shown partly in elevation and partly in longitudinal section upon the line II—II of Fig. 5;

Fig. 3 is a view in end elevation, looking from the left of the machine as seen in Fig. 1, parts being broken away to reveal certain details more clearly;

Fig. 4 is a view showing the head of the machine in rear elevation;

Fig. 5 is a plan view of the machine;

Fig. 6 is a cross section upon the line VI—VI of Fig. 3; and

Figs. 7, 8, 9, 10, 11 and 12 are views illustrating details of the feet and legs of the welt support.

The sole attaching machine comprises a frame 10 upon which is mounted a bracket 12. The outer end of this bracket supports a pad box 14 containing a pressure pad 16 which may either be solid or filled with water or compressed air in a manner already known in the art.

The bracket 12 also carries an upright 18 braced to the frame 10 by diagonal bars 20 (see Figs. 3 and 4). A walking beam pressure applying member 22 is secured to a shaft 24 which is journaled in bearings 26 in the upper portion of the upright 18. The rear end of the walking beam 22 is pivotally connected to a piston 28 which operates vertically in a stationary cylinder 30 bolted upon the bracket 12. A pipe line 32 provides for introducing fluid under pressure to the cylinder at will when it is desired to move the piston upward.

The front end of the walking beam 22 carries a head 34 from which depend a toe post 36 and a heel post 38. The toe post carries a pad 40 (Fig. 2) adapted to bear upon the top of the forepart of the shoe and its upper end is threaded into the head 34 to provide for vertical adjustment, it being secured in adjusted position by a set screw 42 bearing upon a brass or other soft metal plug 44 which engages the threaded upper end of the toe post.

A last pin 46 is pivoted at 48 in the lower end of the heel post 38, an upward extension 50 of the last pin being pivoted to a link 52 surrounded by a compression spring 54 to form a toggle, which, under the influence of the spring, tends to remain in broken condition upon either side of dead center to which it may be moved. When the pin 46 is swung to the right, as seen in Fig. 1, it is in position to receive a last 56 and when the forepart of the shoe 60 upon the last is moved up against the toe pad 40 the toggle 30, 52 will assume the illustrated position and the spring 54 will exert enough force upon the last 56.

to hold the shoe up against the toe pad. The lasted shoe, with a cemented outsole 62 positioned upon it, is now ready to be lowered into contact with the pad 16 to apply sole attaching pressure. This is accomplished by introducing fluid under pressure into the cylinder 30.

Inasmuch as the pad 16 of the sole attaching machine is more or less yielding in character, there is a tendency to roll up the projecting margin of an extension edge sole unless such margin is supported in such a manner as to prevent this from happening. Also, in the case of a welt shoe, it is important that the projecting portion of the welt be supported against the upward pressure applied to the sole margin by the pad in order to insure a firm adhesive bond between the welt and the marginal portion of the sole.

For the purpose of supplying such support for the welt, which is shown at 64, I provide a welt support consisting of a series of independent feet 66 arranged around the forepart of the shoe and adapted to be fitted into the welt crease and locked against vertical yielding before the pressure is applied. Each of the feet 66 is separately carried by a leg comprising a lower section 68 and an upper section 70 connected by a universal joint 72 of the ball and socket type arranged to permit the leg section 68 to swing in any direction. The upper leg section 70 is slidably arranged in guide holes passing through a plate 74 bearing against the under side of the head 34 and a carrier 76 which is guided for vertical movement upon the toe post 36 and upon a sleeve 78 which depends from the plate 74 (see Fig. 2). Expansion springs 80 between the plate 74 and the carrier 76 tend constantly to keep the plate and carrier apart but permit the plate to be moved downward toward the carrier for a purpose now to be described.

Each upper leg section 70 is surrounded by a slidable sleeve 82 between which and the carrier 76 in an expansion spring 84. A locking dog having a nose 86 and a tail 88 is pivoted at 90 between ears 92 upon the sleeve 82. The rounded end of the tail portion 88 of the dog is received in an annular groove 94 in the carrier 76. Normally the sleeve 82 is lifted by the spring 84 until the nose 86 of the locking dog engages the upper leg section 70, locking the sleeve to said leg section so that when the carrier 76 is depressed in the pressure applying operation of the machine, carrying the locking dog downward with it, the welt supporting leg is also carried downward positively through the same distance.

In order to provide for unlocking the welt supporting leg from the carrier 76 the plate 74 is adapted to be depressed by a cam 96 operated by a handle 98 pivoted at 100 to the head 34. When the plate 74 engages the upper ends of the sleeves 82 they will all be simultaneously lowered against the tension of the springs 84 until the bite of the locking dogs upon the welt supporting legs 70 is released. When this condition obtains, the legs may be moved up or down easily through the carrier 76 and the plate 74, a friction plug 102 pressed upon by a spring 104 being provided in connection with each leg to sustain the leg in any vertical position at which it is left.

In order to swing the lower leg sections 68 and the welt supporting feet 66 into or out of the welt crease of the shoe, such swinging occurring about the ball and socket joints 72, each lower leg section 68 is connected through a pull spring 106 and a pivoted strut 108 to a pin 110 which is screw threaded for vertical adjustment through a table

112 carried by a hub 114 guided to slide vertically upon a sleeve 116 which surrounds the toe post 36. Vertical sliding movement is imparted to the hub 114 by a bell crank lever 118 which is pivoted at 120 in a bracket 122 depending from the carrier 76, one arm of the lever 118 being pivotally connected at 124 to the sliding hub 114 and the other end of the lever carrying a roll 126 arranged to be engaged by an actuating bar 128 in response to a treadle operation to be described later. The spring 106 and the pivoted strut 108 are connected to the leg section 68 by a clip 130 and the tip of the strut is pointed to engage in a notch 132 in the side of the pin 110.

From the foregoing it will be apparent that when the table 112 is lowered the welt supporting feet 66 will be swung yieldingly inward toward the shoe by the pull exerted upon the springs 106, the parts being in approximately the relation illustrated in Fig. 2. When the table 112 is raised the points of the struts 108 will engage in the notches 132 in the pins 110 and the leg sections 68 and the feet 66 will be swung outward away from the shoe to distances determined by the vertical adjustment of the pins 110. A spring 134 interposed between the carrier 76 and the left hand arm of the lever 118 tends to move the lever in a counterclockwise direction about the pivot 120 and to lower the table 112, drawing the feet 66 into engagement with the welt crease of the shoe. Movement in the opposite direction is effected by moving the actuating bar 128 into engagement with the roll 126, causing the lever 118 to be turned in a clockwise direction about its pivot 120. This movement of the actuating bar 128 may be accomplished by hand, foot treadle or power. As shown, the bar 128 is pivotally supported at its upper end by a link 136 which is pivoted to the upright 18 at 138 and the lower end of the bar is pivoted to a link 140, which in turn is pivoted to the upright 18 at 142, the result being that when the links 136 and 140 are swung about their pivots in a counterclockwise direction the bar 128 is moved into engagement with the roll 126, the table 112 is lifted, and the welt supporting feet are swung outward away from the shoe. A connecting link 144, shown in dotted lines in Figs. 1, 4 and 5, joins the swinging link 140 to the upper end of an arm 146 which is secured to a rock shaft 148 having a lever 150 upon its outer end. A pull spring 152 tends to draw the arm 146 to the right, as viewed in Fig. 1, moving the actuating bar 128 away from the roll 126 and permitting the spring 134 to depress the table 112 and close the welt support around the shoe. The lever 150 may be manually or treadle actuated to open the welt support.

The toe post 36 is surrounded by a heavy compression spring 152 which is interposed between the welt support carrier 76 and the head 34 whereby the carrier and the welt support are permitted to yield upward slightly upon the toe post in case the toe pad 40 should yield sufficiently under the pressure applied by the machine to cause excessive downward pressure to be exerted upon the welt.

As illustrated, the welt support as a whole comprises fourteen welt engaging feet 66 and these with their associated supporting legs are in general of similar construction, but there are differences in the details of some of them. Identifying them by the letters of the alphabet from A to N, as in Fig. 5, those designated by D and J are provided with the sole positioning gages illustrated in Figs. 9, 10, 11 and 12, Figs. 9 and 10 75.

showing the gage associated with the element J, and Figs. 11 and 12 showing that associated with the element D. Referring to Figs. 9 and 10, the foot 66 is provided with an outward extension 5 154 having cut in it a T-slot to provide guiding means for a slide 156 which carries a sole edge engaging finger and is moved yieldingly toward the sole edge by a spring 160. The end of the finger 158 is corrugated, as shown at 162, to permit the gage finger to grip the sole edge securely.

As illustrated in Figs. 11 and 12, the gage construction differs from that just described in that the spring 160 is omitted and a positively acting manually operated adjusting lever 164 is connected by an eccentric pin 166 to the slide carrying the gage finger 163, the construction being such that after the gage has been set it will not yield relatively to the foot plate 66, but all the 10 yielding necessary to accommodate the gage mechanism variation in the width of the sole relatively to that of the shoe at the welt crease will occur in the gage at position J. All of the 15 welt supporting feet are pivoted to their respective legs as shown at 170 to permit them to conform 20 readily to the vertical contour of the surface of the welt.

The three supporting feet at positions F, G and H around the toe end of the shoe are also provided with tilting means illustrated in Figs. 2 25 and 7, wherein the pivot 170 is carried by a lever 172 which is pivotally mounted at 174 in the forked lower link section 68 and has a segmental upper end which occupies a notch 176 in a draw bolt 178 which may be tightened or loosened by 30 turning a thumb nut 180, thus permitting these 35 three welt engaging elements to be tilted to meet the requirements at their locations.

Inasmuch as the aggregate length of the fourteen feet 66 is sufficient to encompass a shoe of 40 large size, it is desirable to provide for the removal of one or two of them when it is desired to 45 constrict the welt support to fit a shoe of small size. Provision for this is illustrated in Figs. 7 and 8 in which the swinging leg sections of the welt 50 supporting elements at positions F and H are illustrated as equipped with a shiftable connection between the leg section and the strut 108. In this case, the clip 130 is replaced by a slide 182 having in its lower face two notches 184 either 55 of which is engageable by a spring pressed finger 60 operated latch 186. When the latch 186 is in the inner notch, as illustrated in Fig. 8, the leg 68 is operated in the same manner as the other legs of the series, but when the latch is released 65 and the slide 182 is pushed to the right until the latch engages in the outer notch 184 the point of the strut 108 is permanently engaged in the notch 182 and the leg 68 always stays swung outward far enough not to interfere with the closing 70 together of the remaining welt engaging feet to fit the small size shoe. This throwing of the elements at positions F and H into or out of action requires but a moment and greatly facilitates the accommodation of shoes of a large range of sizes.

65 By reason of the extra inward force required to be applied to the elements carrying the sole gages, the swinging leg sections 68 at positions D and J are connected positively, but adjustably, to the table 112 instead of through springs like those 70 shown at 106. In this case the vertically adjustable pin 188 is threaded into the table 112 in the same manner as the pins 110, but is positively connected by a link 190 to the clip 130 upon the leg 68. The gage 168 is therefore moved positively to a predetermined position and serves to de-

termine the transverse position of both the sole and the shoe.

The feet 66 are formed variously according to their positions, but in all cases taper to a thin edge adapted to enter the welt crease of a shoe. 5 For example, the foot at position A has a long shank portion 192 (Fig. 2) to permit it to reach in under the overhanging portion of the lasted upper at the inside of the shoe back of the ball line. Others of the series of welt engaging feet 10 156 are made double ended as shown at 194, 196 in Fig. 3, one edge portion being wider than the other. Inasmuch as the foot may be readily reversed by merely loosening one of the screws of the clip 130, either the wide edge portion 196 15 or the narrow edge portion 194 may be used as required by the nature of the work in hand.

The operation is as follows: The lever 150 being lifted, the welt supporting elements are all thrown outward away from the space to be occupied by the shoe. A lasted shoe is jacked upon the last pin 43, the toe portion of the shoe being positioned against the toe pad 49 where it is held by the last pin spring 54.

The lever 150 is now released, permitting the 25 spring 152 to move the actuating bar 128 out of contact with the roll 126 whereupon the spring 134 acts to lower the table 112 and swing the lower leg sections 68 and the feet 66 carried thereby 30 inward into engagement with the shoe. If the 35 welt support as a whole does not conform exactly to the vertical contour of the welt crease of the shoe, the cam 96 is thrown over by depressing the handle 98 thus lowering the table 114 upon the sleeves 82 and unlocking all of the upper leg 40 sections 70 so that the welt support may easily be conformed to the welt crease. The handle 98 is then thrown up, permitting the springs 80 to raise the table 114, and the springs 84 to lift the sleeves 82 and simultaneously lock all the welt 45 supporting legs to the carrier 76.

If the sole 62 has not already been spotted upon the shoe, it is now placed in position between the sole gages 158, 168 and the parts are as illustrated in Figs. 1, 2 and 3 of the drawings. Fluid under 50 pressure is now admitted to the cylinder 30 causing the piston 28 to rise and the head 34 to descend, moving the shoe downward and pressing it heavily upon the pad 46. Inasmuch as the welt 55 support is locked to the carrier 76 which in turn is mounted upon the toe post 36, it will be seen that there is no possibility of the welt support yielding upward under the pressure exerted by the pad 46, with the exception of the slight amount of yield permitted by the heavy spring 152 in case 55 the toe pad 40 should yield slightly, and that the projecting welt and sole extension will be kept flat and pressed tightly together so that a firm adhesive bond between them will result.

After the necessary time interval, the pressure 60 is released and the head 34 rises, carrying the shoe upward to the position shown in Fig. 1. The lever 150 is now lifted, causing the welt support to be opened and the shoe to be released so that it can be removed from the machine.

Having described the invention, what is 65 claimed as new and desired to be secured by Letters Patent is:

1. In a sole attaching machine, a carrier, a welt support comprising a series of feet which are independently movable vertically in the carrier to conform the support as a whole to the welt crease of a shoe, and means for simultaneously locking all of said feet against vertical movement.

2. In a sole attaching machine, a welt support 75

comprising a series of welt engaging elements a carrier in which said elements are independently movable vertically to conform the support as a whole to the vertical contour of the welt crease of a shoe, and means for simultaneously locking all of said elements in their conformed positions.

3. In a sole attaching machine, a welt support, a carrier in which said support is mounted to yield in a direction normal to its welt engaging face, and means for locking the support in said carrier with its welt engaging face in position to engage the welt of a shoe.

4. In a sole attaching machine, a sectional welt support of which the sections are mounted to yield vertically independently, and means for simultaneously locking all the sections together.

5. In a sole attaching machine, a yieldingly mounted carrier, a welt support mounted in the carrier to yield easily relatively thereto, and means for locking the welt support unyieldingly in the carrier.

6. In a sole attaching machine, a yieldingly mounted carrier, a sectional welt support of which the sections are mounted to yield independently in the carrier, and means for locking all the sections unyieldingly in the carrier.

7. In a sole attaching machine, a carrier, a welt support frictionally supported in the carrier, and means for locking the welt support to the carrier.

8. In a sole attaching machine, means for applying pressure to the outsole of a shoe, a frictionally supported, yieldable welt support arranged to oppose the pressure applying means, and means for locking the welt support against yielding in its frictional support.

9. In a sole attaching machine, a welt supporting foot, a leg to which said foot is attached, a universal joint in said leg, and a carrier in which said leg is slidably supported.

10. In a sole attaching machine, a welt support comprising a plurality of feet, each adapted to enter the welt crease of a shoe, a plurality of legs, each carrying one of said feet, supporting means for said legs, and a universal joint in each leg.

11. In a sole attaching machine, a welt support comprising a plurality of welt engaging sections each of which is independently mounted for both vertical and lateral movement, to permit the support as a whole to conform to the welt crease of a shoe.

12. In a sole attaching machine, a welt support, a carrier in which said support is mounted to yield in a direction normal to its welt engaging face, automatic locking means normally preventing the support from yielding, and manually operable unlocking means operable to permit the support to yield.

13. In a sole attaching machine, a double ended welt supporting foot having welt supporting ends of different lengths, said foot being mounted reversibly to permit either end to be engaged at will in the welt crease of a shoe.

14. In a sole attaching machine, a welt supporting foot, a leg to which said foot is attached, a universal joint in said leg, a movable slide, a yieldable connection between the slide and the leg, and means for moving the slide to swing the leg and foot yieldingly about said universal joint.

15. In a sole attaching machine, a welt support comprising a plurality of independently movable welt engaging sections, means for moving all of said sections into the welt crease of a shoe, means for moving all of said sections outward, away from the shoe, and means operable at will to maintain one or more of said sections in outward position, away from the shoe.

JOHN B. HADAWAY. 40
